[57] CLAIM

The ornamental design for a combined golf bag clip and cigar and cigarette holder, as shown and described.

DESCRIPTION

FIG. 1 is a perspective view showing my new design;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof; and,

FIG. 8 is a perspective view showing both a cigar and cigarette (in broken lines), being held in the device.

The broken line portions in FIG. 8 are for illustration only, and form no part of the instant design.
